(57) **CLAIM**

The ornamental design for a dual handle bottle, as shown and described.

DESCRIPTION

FIG. 1 is a perspective view of our dual handle bottle in accordance with our invention;

FIG. 2 is a side view thereof;

FIG. 3 is an opposing side view thereof;

FIG. 4 is a front view thereof;

FIG. 5 is a rear view thereof;

FIG. 6 is a top view thereof; and,

FIG. 7 is a bottom view thereof.

The broken lines shown in the drawings depict portions of the dual handle bottle that form no part of the claimed design.
